UNITED STATES PATENT OFFICE.

ROBERT C. GRAHAM, OF EVANSVILLE, INDIANA.

DESIGN FOR A BOTTLE.

49,730.

Specification for Design.

Patented Oct. 3, 1916.

Application filed June 30, 1916. Serial No. 106,980. Term of patent 14 years.

To all whom it may concern:

Be it known that I, ROBERT C. GRAHAM, a citizen of the United States, and a resident of the city of Evansville, county of Vanderburgh, and State of Indiana, have invented a certain new, original, and ornamental Design for a Bottle, of which the following is a specification, reference being had to the accompanying drawing, forming a part thereof.

Figure 1 is a perspective view of a bottle illustrating said design. Fig. 2 is a horizontal section showing the conformation of said design on the line 2, 2 in Fig. 1. The dotted

portion on the neck of said perspective view in Fig. 1, indicates a frosted portion at said neck.

I claim:

The ornamental design for a bottle as shown and described.

In testimony whereof, I have signed my name to this specification in the presence of two subscribing witnesses:

ROBERT C. GRAHAM.

Witnesses:

E. R. HARRELL,
LOTTIE VOLLMER.
